MACHINE FOR ROOTING HAIR INTO
DOLL'S HEAD

Frank A. Richards, Hollis, and Ragnar W. Winberg,
Floral Park, N.Y., assignors to Ideal Toy Corporation,
Hollis, N.Y., a corporation of New York
Filed Jan. 10, 1962, Ser. No. 165,453
8 Claims. (Cl. 112—79.5)

The present invention relates generally to a machine for rooting hair into a doll's head, and in particular to a hair-rooting machine of the chain-stitch type which embeds hair-stimulating filaments or threads into the skull area of the doll head and simultaneously draws and severs loops to form a body of hair on the doll's head.

In the manufacture of dolls of the type including a head fabricated of a penetratable plastic, it has become the prevalent practice to embed or root hair-simulating threads or yarns of synthetic fibers and the like into the skull area to create a body of hair permanently affixed to the doll's head, and to subsequently style of hairdo for the doll by appropriate cutting and trimming of the rooted body of hair. A number of different types of machines have become available for simultaneously rooting hair into the doll's head by a series of interlocking chain stitches, drawing successive loops to a prescribed length, and cutting the loops at a point medially thereof and remote from the doll's head such that the opposite legs of the drawn loops provide individual hairs projecting from the doll's head. Machines for this purpose are adaptations of the well-known chain stitch sewing machine of the type manufactured by Puritan Sewing Machine Company, of Boston, Massachusetts. This well known type of sewing machine includes one or more needles which move through stitch-forming cycles having forward skull-penetrating strokes during which the one or more needles pass upwardly through the doll's head and into a hair-pickup position. Provision is made to pass or wrap the simulated hair about the needles when in the hair-pickup position for engagement by the needle hooks such that when the needles move through the backward chain-forming strokes and re-enter the doll's head a loop is formed. The thus formed loops are drawn to a prescribed length and are severed into substantially equal lengths which provide two hairs for each such severed loop. Provision is made during the skull-penetrating stroke to clamp the doll's head against a work support by a presser foot; and at the appropriate time in the stitch-forming cycle, the presser foot is released from the doll's head and the needle is rocked in a direction to displace the doll's head relative to the work support for the next stitch-forming cycle. For a further description of this type of machine, reference may be made to U.S. Patent No. 2,812,734 of November 12, 1957, in the name of Frank A. Richards, which patent is assigned to the assignee of the present application, as well as to the numerous prior art patents owned by Puritan Sewing Machine Company.

Broadly, it is an object of the present invention to provide and improve hair-rooting machine of the aforesaid general construction.

Actual experience with machines of this type indicates the need for less complicated and more reliable mechanisms for drawing and cutting the loops in timed relation to the formation of successive chain stitches into the doll's skull. In particular, it is relatively important to have a machine which is readily changed over from the formation and cutting of loops of one length to the formation and cutting of loops of a different length, with a relatively large range of adjustment. The changeover of the machine should be achieved with a minimum amount of down time and without the need of either difficult to

2

make or precise adjustments. In commercial practice, it is not uncommon to require the formation of hair lengths anywhere from three inches to eight inches, and it has been heretofore impractical or impossible to provide for a reasonable range of adjustment in available types of machines. It is further important that the facility for ready adjustment be accomplished in a manner compatible with high-speed operation, and of course without interfering with the ability of the machine operator to guide the doll's head in relation to the chain-stitching mechanisms to stitch the many and varied types of hair pieces which are required in commercial use.

Accordingly, it is a further object of the present invention to provide a machine for rooting hair into a doll's head which is capable of ready adjustment over a range of hair lengths. Specifically, it is within the contemplation of the present invention to provide a hair-rooting machine which is exceptionally versatile and capable of stitching various hair lengths, is easily controlled by the machine operator particularly with respect to the facility of movement of the doll's head in relation to the stitching mechanisms, assures virtually perfect and even cutting of the successive hair loops drawn by the machine, and provides substantially trouble-free operation over prolonged periods of use with minimum in-service adjustment.

In accordance with an illustrative embodiment demonstrating objects and features of the present invention, there is provided a machine for rooting hair into a doll's head which comprises a support, chain-stitching mechanisms including a needle movable through a stitch-forming stroke for chain-stitching hair into the doll's head, and cutting mechanism spaced from the needle and mounted on a support. Means are provided for releasably securing the hair cutting mechanisms in an adjusted position in relation to the needle thereby establishing the length of the hair to be rooted into the doll's head. A loop-drawing carriage including a hair guide is mounted for cyclic movement in a loop-drawing path which includes a needle-engaging segment in which the hair is engaged about the needle and a cutter-engaging segment during which the hair is engaged in the hair-cutting mechanisms. Means are provided for adjusting the length of the loop-drawing path to correspond to the adjusted position of the hair-cutting mechanisms. Respective actuating means are provided for moving the carriage along the adjusted loop-drawing path and for actuating the hair-cutting mechanisms in order to sever hair loops in timed relation to the operation of the chain-stitching mechanisms.

The above description, as well as further objects, features, and advantages of the present invention, will be more fully appreciated by reference to the following detailed description of a presently preferred, but nonetheless illustrative embodiment according to the present invention, when taken in conjunction with the accompanying drawings:

FIG. 1 is a side elevational view, with some parts broken away and in section, of a hair-rooting machine demonstrating features of the present invention;

FIG. 2 is a plan view of the machine shown in FIG. 1, with the thread guides being disposed substantially at the start of the needle-engaging segment of the loop-drawing path;

FIG. 3 is a fragmentary plan view, showing the loop-drawing carriage which moves between the needles of the chain-stitching mechanisms and the hair-cutting mechanisms, with the thread guides being disposed along the needle-engaging segment at a point somewhat later in the loop-drawing path than that illustrated in FIG. 2;

FIG. 4 is a plan view similar to FIG. 3, with the dot-dash lines showing the position of the hair guides in relation to the cutting mechanisms at the start of a cutter-

engaging segment of the loop-drawing path and with the full lines showing the hair guides substantially at the end of the cutter-engagement segment of the loop-drawing path;

FIG. 5 is side-elevational view of the sub-assembly shown in FIG. 4, with the dotted lines to the right showing successive positions of the needles demonstrating the conventional feeding action of the chain-stitching mechanism;

FIG. 6 is a plan view similar to FIG. 4, with the full lines showing the position of the hair guides during the forward traverse segment and with the dotted lines showing an oriented position of the hair guides after traverse of the guide-orienting segment of the loop-drawing path; and

FIG. 7 is a diagrammatic plan view showing the various segments of the loop-drawing path in relation to the plural needles and the hair-cutting mechanisms.

Referring now specifically to the drawings, there is shown in FIGS. 1 and 2 a typical chain-stitch sewing machine, generally designated by the reference numeral 10, which may be modified in accordance with the present invention to provide for the rooting of simulated hair into the skull of a doll's head, a portion of a typical head or work piece being shown in FIG. 1 and designated by the letter W. The chain-stitch sewing machine 10 includes a work support or foot 12 over which the doll's head or work piece is advanced due to the four-motion feeding action of the plural needles 14, 16, and 18 each of which has a forwardly directed hook (i.e., hook 14a, in FIG. 2) at the upper end thereof. The plural needles 14, 16, and 18, are mounted by conventional mechanisms for movement through four-motion stitch-forming cycles, as shown diagrammatically in FIG. 5. The stitch-forming cycles include a return stroke S₁ from a retracted position, a forward and upward skull-penetrating stroke S₂, a feeding stroke S₃ into a hair-pickup position, and finally a backward chain-forming stroke S₄.

Referring once again to FIGS. 1 and 2, the chain-stitch sewing machine 10 incorporates a standard 20 which carries a horizontally extending head 22 in which is journaled a main shaft, designated by the reference numeral 24 and shown in dot-dash lines in FIG. 1. The main shaft 24 is coupled by conventional mechanisms to a vertically reciprocating presser foot bar 26 which carries a U-shaped presser foot 28 including a substantially horizontally extending work-engaging shoe 28a overlying the work support 12. Normally, the work-engaging shoe 28a of the presser foot 28 engages the doll's head W for the required chain-stitching operation; and at the appropriate time in the machine cycle during the forward or feeding stroke S₃ of the needles, the work-engaging shoe 28a is lifted by the presser foot bar 26 to permit the movement of the doll's head relative to the work support 12 for the next stitch-forming cycle. For further details of this substantially conventional chain-stitch sewing machine, reference may be made to U.S. Patent No. 2,812,734, of November 12, 1957, assigned to the assignee of the present application, and to the numerous prior art patents to Puritan Sewing Machine Company.

Rearwardly of the head 22 of the chain-stitch sewing machine 10, there is provided an appropriate frame or support which includes a vertically-extending mounting standard 30 which carries upstanding mounting plates 32, 34, extending fore and aft of the machine 10 and supported on the upstanding mounting standard 30. The mounting plate 34 carries a depending track-supporting angle iron 36 and a horizontal track-supporting angle iron 38. Extending forwardly of the machine from the horizontal track-supporting angle iron 38 is a horizontal carriage track 40 which is offset to one side of the vertically reciprocating needles 14, 16, and 18. Disposed below the carriage track 40 at a location offset to one side thereof and parallel thereto is a cutter rail 42 which is suspended by a rail-supporting standard 44 from the carriage track 40 at a location behind the needles.

In accordance with the present invention, hair-cutting mechanisms, generally designated by the reference numeral 46, are adjustably mounted on the cutter rail 42 in spaced relation rearwardly of the plural needles 14, 16, and 18. The hair-cutting mechanisms 46 include a cutter mounting block 48 which is slidably mounted on the cutter rail 42 for movement toward and away from the needles 14, 16, 18. The adjusted position of the cutter-mounting block 48 in relation to the needles will determine the length of the hair rooted into the doll's head or similar work piece, with the adjusted position of FIGS. 1 and 2 corresponding substantially to the longest hair which can be rooted and cut in accordance with the present invention. The cutter-mounting block 48 may be secured in its various adjusted positions along the cutter rail by the provision of one or more securement bolts 50. The cutter-mounting block 48 supports a carrier 52 which includes a base wall 52a lying over the cutter rail 42 and an upstanding front wall 52b, which terminates in a rearwardly directed nose or hook 52c over which successive hair loops are engaged, as will be subsequently described. At approximately the level of the work-engaging shoe 28a of the presser foot 28, the upstanding wall 52b of the carrier 52 supports a stationary cutter blade 54 which cooperates with a movable cutter blade 56 for severing successive hair loops. The movable cutter blade 56 in turn is mounted on a movable cutter mount 58 which is slidably supported for limited reciprocation on rails 60 on the carrier 52. When the movable cutter blade 56 is spaced in relation to the stationary cutter blade 54, as illustrated in FIG. 1, hair loops may be disposed therebetween; and as the movable cutter blade 56 reciprocates through its forward or cutting stroke toward the stationary cutter blade 54 and into the cutting position illustrated in FIG. 5, hair loops are severed.

In this illustrative embodiment, the necessary reciprocating motion is imparted to the movable cutter mount 58 and to the movable cutter blade 56 by a cutter-actuating rod 62 which is reciprocated from the main shaft 24 of the sewing machine 10. Specifically, and as seen best in FIG. 1, the main shaft 24 is provided with a cutter-operating eccentric 64 which is engaged by an eccentric follower 66. The eccentric follower is coupled to the cutter-actuating rod 62 by a double-arm lever 68 which is pivoted by a relatively loose pivot 70 in a pivot block 72 on the head 22 of the machine 10, with the driver arm 68a thereof connected to the eccentric follower 66 and the rocker arm 68b thereof coupled to the cutter-actuating rod 62. The horizontal component motion of the rocker arm 68b is coupled to the cutter-actuating rod 62, while the vertical component of motion is lost in the play of the pivot 70 in the bearing 72.

A loop-forming carriage, generally designated by the reference numeral 74, is mounted on the carriage track 40 for reciprocation between a forward limit position in operative relation to the plural needles of the chain-stitching mechanisms and a retracted limited position (shown by the dotted lines in FIG. 1) in operative relation to the hair-cutting mechanisms 46. The forward position of the carriage 74 is the same for various hair length adjustments of the hair cutting mechanisms 46. However, the retract position is adjusted in accordance with the ultimate length of the hair desired and the corresponding setting of the hair-cutting mechanisms 46.

The forward limit position for the carriage 74 is established by a fixed forward carriage-engaging limit assembly 76, while the retracted limit position for the carriage is established by an adjustable rearward carriage-engaging limit assembly 78. The forward carriage-engaging limit assembly 76 includes a mounting shoe 80 which is fixed to the forward end of the cutter rail 42 and to the forward end of the carriage track 40 (see FIG. 1). Mounted on the shoe 80 is a vertically movable friction pad 82 which is biased upwardly to engage the adjacent undersurface 75 of the carriage 74 in the forward limit position of the

latter. The rearward carriage-engaging limit assembly 78 includes an adjustable mounting shoe 84 which may be slid to various adjusted positions along the carriage track 40 and secured in such adjusted position by an appropriate mounting bolt 86. The mounting shoe 84 carries a vertically movable friction pad 88 which is biased upwardly to engage the undersurface of the carriage 74 in the adjustable retracted position. The mounting of the respective friction pads 82, 88 on the shoes 80, 84, are substantially identical and are exemplified by the showing to the left in FIG. 1 wherein it is seen that the friction pad 88 is mounted on upstanding studs 90 which extend through the shoe 84 and carriage respective nuts or stops 92 which limits the vertical movement of the pad 88 relative to the shoe 84. The shoe 84 in the areas surrounding the studs 90 is provided with cavities which receive coil springs 94 which bear at their lower ends against the shoe and at their upper ends against the upper surface of the friction pad 88 to bias the same upwardly for engagement with the carriage 74. An appropriate yieldable friction facing is provided on the friction pads, 82, 88 and the opposite lower ends of the loop-forming carriage 74 are chamfered to facilitate smooth engagement of the carriage with the respective friction pads and movement into the limit positions established by the friction pads.

The carriage 74 has pivotally mounted thereon a hair guide 96 which includes a dependent inclined guide arm 98 carrying spaced vertically-extending hair guide tubes 100, 102, 104, a transversely-extending crosshead 106 rigid with the guide arm 98, and a cam arm 108 rigid with the crosshead 106. The cam arm 108 extends generally parallel to the guide arm 98 and carries a cam follower 110 which engages a cam 112 fixed to the carriage track 40 and provided with a cam track 114, for a purpose to be subsequently described. The hair guide 96 is pivotally mounted on the carriage 74 at a hair guide pivot 116 at the junction between the guide arm 98 and the crosshead 106. The guide arm 98 is inclined downwardly and forwardly (see FIG. 1) such that the guide tubes 102, 104, 106 are supported for swinging movement in a horizontal plane, with the lower end of the guide tubes being disposed substantially at the level of the hooks on the plural needles. In response to reciprocation of the carriage 74 along the carriage track 40 and pivotal movement of the guide 96 about its pivot 116, the guide tubes 100, 102, 104 are moved along a loop-forming path, to be subsequently described in detail, the path includes an operative position relative to the plural needles 14, 16, 18 for engaging respective hairs or filaments H₁, H₂, and H₃ about the respective needles and an operative position in relation to the stationary and movable cutter blades 54, 56 of the hair-cutting mechanism 46 wherein the opposite ends of the loops are positioned for cutting. The pivotal or swinging movement of the hair guide 96 in the horizontal plane about the upstanding pivot 116 is limited by adjustable stops 118, 120, mounted on the carriage 74 at the rear and front edges thereof and at opposite sides of the crosshead 106.

Actuating mechanisms are provided for reciprocating the carriage 74 along the carriage track 40 and for pivoting the hair guide 96 in relation to the carriage 74 in timed relation to the operation of the chain-stitching mechanisms to complete successive loops of the plural hairs about the needles 14, 16, 18 and over the nose 52c of the hair-cutting mechanism 46. In this illustrative embodiment, an auxiliary drive shaft 122 is disposed in spaced parallel relation behind the main shaft 24 of the sewing machine 10 and is journalled on the upstanding mounting plates 32, 34. The auxiliary drive shaft is coupled to the main guide shaft by a drive sprocket 124 on the main drive shaft, a driven sprocket 126 on the auxiliary shaft 122, and an interconnecting chain 128 trained over the sprockets 124, 126 (see FIG. 2). The auxiliary drive shaft 122 carries an actuating eccentric

130 (see FIG. 1) which is engaged by an eccentric follower or ring 132 having an upstanding follower arm 134. The reciprocating motion of the follower arm 134 is imparted from the double arm actuating lever 136 to a coupling rod 138 via a pivotal connection 140. The coupling arm 138 in turn has a pivotal connection 142 to the hair guide 96 at the junction of the crosshead 106 and the cam arm 108 (see FIG. 2). The double arm actuating lever 136 is coupled to the follower arm 134 and mounted in a fashion to permit the adjustment of the fore and aft reciprocation of the assembly of the carriage 74 and the hair guide 96 in accordance with the desired length of hair to be formed by the machine, but with provision for establishing the same forward limit position for the carriage 74 and the guide tubes 100, 102, 104 of the hair guide 96 since the needle location is fixed in the machine. Specifically, the double arm actuating lever 136 has a pivotal mount 144 which may be adjusted fore and aft of the machine to establish a constant forward position for the hair guides. Specifically, the pivotal mount 144 is journalled in a bearing sleeve 146 which is carried by a follower block 148 mounted in a horizontally-extending slideway 150. In the illustrated position of FIG. 1, the slide block 148 is at the left extremity of the slideway 150 corresponding to an adjustment of the machine for the longest possible hair. The slide block 148 is adjusted along the slideway 150 by the provision of a lead screw 152 (see FIG. 2) which is in threaded engagement with the slide block or follower 148 and is journalled on a laterally projecting ear 34a on the mounting plate 34. A knurled knob 154 is provided on the lead screw 152 to facilitate adjustment of the follower or slide block 148 along the slideway 150. The follower arm 134 of the eccentric follower ring 132 is pivotally connected to the driver arm 136a of the double arm actuating lever 136 by the provision of a pivotal connection 156 which may be pivotally secured at various adjusted positions along the slot 158 provided in the arm 136a which slot extends away from the adjustable pivotal mount 144 of the double arm lever 136. It will be appreciated that the ratio of the length of the driver arm 136a between the pivotal mount 144 and the pivotal connection 156 and the entire length of the driven arm 136b between the pivotal mount 144 and the pivotal connection 140 will determine the throw or stroke length available at the assembly of the carriage 74 and the hair guide 96. The stroke or throw may be adjusted by loosening the pivotal connection 156 between the follower arm 134a and the driver arm 136a and sliding the pivotal mount 144 along the slideway 150 by turning the knurled knob 154 on the lead screw 152. When the adjusted position for the pivotal mount 144 is established, the pivotal connection 156 between the follower arm 134 and the driver arm 136a is once again completed, with the follower arm 134 extending generally vertically. In such adjusted position, it will be appreciated that the effective length of driver arm between the pivotal mount 144 and the pivotal connection 156 (which will be disposed somewhere along the slot 158) will be greater and the ratio of the lever arms correspondingly decreased to establish a shorter throw for the assembly of the carriage 74 and the hair guide 96. Of course for each such setting of the actuating lever 136 and its corresponding connections, appropriate settings must be made for the hair-cutting mechanism or unit 46 and for the rear carriage-engaging limit assembly 78, as will be subsequently described.

Progressive reference will now be made to FIGS. 3 to 7 inclusive for a description of a typical machine cycle in accordance with the present invention:

As seen in FIG. 3, the hair guide 96 is pivoted to an offset position bearing against the rear stop 118 by virtue of the rearwardly directed pulling force exerted on the coupling rod 138, as indicated by the directional arrow. This pulling force is provided by the driven arm 136b

of the actuating lever in response to the operation of the cam and follower 130, 132 under control of and in timed relation to the rotation of the main shaft 24. At this time in the machine cycle, the needles 14, 16, 18 are in the hair-pickup positions (see FIG. 1) and the respective guide tubes 100, 102, 104 are forwardly of the needles such that the hairs or filaments H₁, H₂, H₃ are in position to be engaged about the corresponding needles. As the assembly of the hair guide 96 and the carriage 74 starts rearwardly, there can be no relative pivotal movement of the hair guide 96 in relation to the carriage 74. The respective guide tubes 101, 102, 104 depend from the guide arm 98 such that the guide tube 100 may enter the interstice between the needles 14, 16, the guide tube 102 can enter the interstice between the needle 16, 18, and the guide tube 104 can pass along the outer side of the needle 118 at the start of a return stroke, as shown diagrammatically in FIG. 7 and designated generally by the letter A. As the coupling rod 138 pulls rearwardly, the carriage 74 is disengaged from the friction pad 82 of the front carriage-engaging limit assembly 76 and the guide tubes 100, 102, 104 move rearwardly along a first loop-forming segment B toward the hair-cutting mechanisms 46 during which one leg of a hair loop is formed. At the end of the rearward reciprocation of the carriage 74 as established by engagement with the friction pad 83 of the rear carriage-engaging limit assembly 78, the respective thread guides 100, 102, 104 arrive at a laterally offset position in relation to the hair-cutting mechanisms 46, the laterally offset clearance position is shown by the dotted lines in FIG. 4 and is identified by the reference letter, C in FIGS. 4 and 7. Throughout the rearward movement of the thread guides along the first loop-forming segment B of the loop-forming path, it will be appreciated that the crosshead 106 of the hair guide 96 rests against the rear stop 118, since a rearwardly directed pull is exerted by the coupling rod 138 on the pivoted hair guide 96. After the carriage 74 arrives at the rear limit position established by the adjustable carriage-engaging limit assembly 78, and in response to the start of the forward stroke imparted by the eccentric 130 and follower 132 via the double arm actuating lever 136 to the coupling rod 138, as indicated by the directional arrow in FIG. 4, the hair guide 96 swings horizontally about the vertical pivot or pin 116 until the cross head 106 engages the front stop 120. It should be appreciated that the frictional force between the pad 83 and the carriage 74 is sufficient to maintain the carriage 74 in a stationary position until the hair guide 96 reaches the limit of its pivotal movement against the stop 120. In this laterally offset clearance position, designated by the letter E in FIGS. 4 and 7, the respective hair guides 100, 102, 104 are at the opposite side of the cutter assembly. As the hair guides move from one laterally offset position C (as shown by the dotted lines in FIG. 4) to the other laterally offset position E at the opposite side of the hair-cutting mechanism 46 (as shown by the full lines in FIG. 4), the hair guides sweep through an arcuate cutter-engaging segment of the loop-forming path, as shown diagrammatically in FIG. 7 and designated by the letter D. In response to the movement of the hair guides 100, 102, 104 through the cutter-engaging segment D, the respective hair filaments H₁, H₂, and H₃ are wrapped around the upstanding and rearwardly directed nose 52c and dropped into a supported and non-cutting position overlying the stationary and movable cutter blades 54, 56. At this time and as seen in FIG. 5, the blades 54, 56 are closed and cutting the previously formed hair loops. With continued reference to FIG. 5, it will be understood that the timing of the hair-cutting mechanisms 46 in relation to the chain-forming mechanisms is such that there is an appreciable lag between the time when the loop is formed and when the loop is cut to assure that the threading of the machine will not be lost. For example, the loop L₋₁ is being cut to form separated opposite legs and corresponding hairs embedded in the

7
doll's head or work piece W, while the loop L being formed is simultaneously being wrapped about the nose 52c of the hair-cutting unit 46 at one end. At its opposite end, the loop L is being chained or looped through the previously formed loop L₋₁ at the underside of the doll's head by the needle which is moving from its retracted position through the return stroke S₁. Of course, when the movable cutter blade 56 is retracted away from the stationary cutter blade 54, the loop L formed about the upstanding nose 52c will drop into position for severing in response to the next cutting stroke.

Referring again to FIG. 4, it will be appreciated that after the hair guide 96 pivots to the laterally offset clearance position established by the front stop 120 in response to the forward thrust imparted to the coupling rod 138, that the hair guide 100, 102, 104 will move forwardly toward the needles 14, 16, 18 through a second loop-forming segment, shown diagrammatically in FIG. 7 and designated by the letter F. At a time prior to the end of the forward stroke of the coupling rod 138, and in the intermediate position shown by the full lines of FIG. 6 and designated by the letter G in FIGS. 6 and 7, the cam roller or follower 110 engages the inclined camming surface 114a of the cam 114. Thereupon, the continued forward thrust of the coupling rod 138 against the reaction force developed by the cam roller 110 riding along the inclined camming surface 114a will cause the hair guide 96 to pivot about the pin or pivot 116 from the full line position illustrated in FIG. 6 to the dotted line position wherein the hair guides or sleeves 100, 102, 104 are located behind the needles 14, 16, 18 for movement through the needle-engaging segment A of the loop-forming path. The sidewise displacement or pivoting of the thread guides under control of the inclined camming surface 114a is designated in FIG. 7 by the letter J and can be considered to be a sidewise traverse segment of the loop-forming path. The oriented position of the thread guides or sleeves 100, 102, 104 in relation to the needles 14, 16, 18 is designated in FIGS. 6 and 7 by the letter K. In this oriented position, the thread guide or sleeve 100 is in position to wrap the corresponding hair or thread H₁ about the needle 14 as it passes in a curved path about the outer side thereof, the hair guide 102 is in a position to enter the interstice between the needles 14, 16, and to wrap its hair or thread H₂ about the needle 16, and the hair guide 104 is in position to enter the interstice between the needle 16, 18, and to wrap its hair H₃ about the needle 18. Thereupon, and as the cam roller 110 rides up on to the flat camming surface 114b and in response to continued forward thrust imparted to the coupling rod 138, the guides 100, 102, 104 will pass through the needles 14, 16, 18. The cam roller 110 arrives at the junction between the camming surfaces 114a, 114b at a time when the carriage 74 is still moving through its forward thrust or stroke such that the oriented guides will be advanced through the respective needles, as the actuating mechanism completes its forward thrust. As the coupling rod 138 is pulled rearwardly in response to the rearward stroke of the actuating mechanisms, and with the carriage 74 remaining stationary, the thread guide 96 is swung to an offset clearance position wherein the crosshead 106 contacts the rear stop 118 which in turn swings the respective thread guides through the needle-engaging segment A of the loop-forming path for return along the first loop-forming segment B of the loop-forming path, as seen in FIG. 3.

From the foregoing description, it will be appreciated that there has been provided in accordance with the present invention an exceptionally simple and highly reliable attachment for a conventional chain stitch sewing machine which converts the same to the rooting of hair-simulating threads of filament into a doll's head and like work pieces. The adjustments to achieve various hair lengths may be made by the simple expedient of relocating the rear limit stop or assembly for the carriage, adjusting the position

of hair-cutting mechanisms, and making an appropriate adjustment in the stroke or throw imparted to the carriage. These adjustments do not require the physical replacement of any component part of the machine and may be made on a routine day to day basis as required. The region surrounding the work support is free of any obstructions and may be adequately shielded to permit the operator to manipulate the doll's head as is required to stitch in the various complex patterns often required in making up a hair piece with virtually no danger of injury. The timing of the mechanisms of the attachment may be readily coordinated to the timing of the conventional chain-stitch sewing machine and the cutting sequence is such that there is virtually no possibility that the threading will be lost incident to cutting of hairs or filaments at a time when they are not trapped into the doll's head or scalp.

Upon a comparison of the additional mechanisms of the instant hair-rooting machine to the conventional chain stitch sewing machine, it will be appreciated that the carriage 74 and associated mechanisms which wrap the respective hairs about the needles and the hair-cutting mechanisms partially replaces the conventional looper which is found in such chain stitch sewing machine. In the present hair-rooting machine, the conventional looper which is necessary to the operation of the chain stitch mechanisms is removed and replaced by the carriage 74 and associated mechanisms which serve the function of the conventional looper and in addition serves as a means for drawing successive lengths of hair from the source of supply for cutting. The carriage and associated mechanisms serve a dual function as compared to the conventional looper and result in a materially simplified machine, assuring positive and reliable operation.

A latitude of modification, substitution and change is intended in the foregoing disclosure and in some instances some feature of the invention will be used without a corresponding use of other features. Accordingly, it is appropriate that the appended claims be construed in a manner consistent with the spirit and scope of the disclosure.

What we claim is:

1. A machine for rooting hair into a doll's head comprising chain-stitching mechanisms including a needle movable through stitch-forming stroke for chain stitching hair into a doll's head, hair-cutting mechanisms spaced from said needle, a loop-drawing carriage including a hair guide pivotally mounted on said carriage, means for moving said carriage in a loop-drawing path including a needle-engaging segment during which said hair is engaged about said needle and said loop-drawing path further including a cutter-engaging segment during which said hair is engaged in said hair-cutting mechanisms, and actuating means for said hair-cutting mechanisms for severing hair loops in timed relation to operation of said chain-stitching mechanisms.

2. A machine for rooting hair into a doll's head comprising chain-stitching mechanisms including plural needles simultaneously movable through stitch-forming strokes for chain stitching plural hairs into a doll's head, hair-cutting mechanisms spaced from said needles, a loop-drawing carriage including plural hair guides pivotally mounted on said carriage, means for moving said carriage in a loop-drawing path including a needle-engaging segment during which said plural hairs are individually engaged about the respective needles and said loop-drawing path further including a cutter-engaging segment during which said plural hairs are engaged in said hair-cutting mechanisms, and actuating means for said hair-cutting mechanisms for severing hair loops in timed relation to operation of said chain-stitching mechanisms.

3. In a machine for rooting hair into a doll's head, chain-stitching mechanisms including a needle movable through a stitch-forming stroke for chain stitching hair into a doll's head, hair-cutting mechanisms spaced from said needle, a loop-drawing carriage including a hair guide

and means mounting said hair guide on said carriage for pivotal movement relative to said carriage, and means for moving said carriage and said hair guide in a loop-drawing path including a needle-engaging segment during which said hair guide is pivoted relative to said carriage and said hair is engaged about said needle and said loop-drawing path further including a cutter-engaging segment during which said hair guide is again pivoted relative to said carriage and said hair is engaged in said hair-cutting mechanism.

4. A machine for rooting hair into a doll's head comprising chain-stitching mechanisms including a needle movable through a stitch-forming stroke for chain stitching hair into a doll's head, hair-cutting mechanisms spaced from said needle, a loop-drawing carriage including a hair guide and means mounting said hair guide on said carriage for pivotal movement relative thereto, means for moving said carriage and said hair guide in a loop-drawing path including a needle-engaging segment during which said hair guide is pivoted relative to said carriage and said hair is engaged about said needle and said loop-drawing path further including a cutter-engaging segment during which said hair guide is again pivoted relative to said carriage and said hair is engaged in said hair-cutting mechanism, and means for actuating said hair-cutting mechanisms to sever hair loops in timed relation to operation of said chain-stitching mechanisms.

5. In a machine for rooting hair into a doll's head, a support, chain-stitching mechanisms including a needle movable through stitch-forming stroke for chain stitching hair into a doll's head, hair-cutting mechanisms spaced from said needle, a loop-drawing carriage mounted on said support for reciprocal movement, a hair guide mounted on said carriage for pivotal movement relative thereto, and means for moving said carriage and said hair guide in a loop-drawing path including a needle-engaging segment during which said hair guide is pivoted relative to said carriage and said hair is engaged about said needle and said loop-drawing path further including a cutter-engaging segment during which said hair guide is again pivoted relative to said carriage and said hair is engaged in said hair-cutting mechanism, said last-named means including means for reciprocating said carriage, friction means engaging said carriage when the latter approaches a limit position adjacent said needle, and camming means engaging said hair guide when said carriage is in said limited position and responsive to the means for reciprocating said carriage to pivot said hair guide through said needle-engaging segment.

6. A machine for rooting hair into a doll's head comprising a support, chain-stitching mechanisms including a needle movable through a stitch-forming stroke for chain stitching hair into said doll's head, hair-cutting mechanisms spaced from said needle, means adjustably mounting said hair-cutting mechanisms on said support, means for releasably securing said hair-cutting mechanisms in an adjusted position in relation to said needle thereby establishing the length of the hair to be rooted into said doll's head, a loop drawing carriage including a hair guide pivotally mounted on said carriage, means mounting said carriage for reciprocal movement in a loop-drawing path including a needle-engaging segment in which said hair is engaged about said needle and said loop-drawing path further including a cutter-engaging segment during which said hair is engaged in said hair-cutting mechanisms, means for adjusting the length of said loop-drawing path to correspond to said adjusted position of said hair-cutting mechanism, actuating means for said carriage moving the same along the adjusted loop-drawing path, and further actuating means for said hair-cutting mechanisms for severing hair loops in timed relation to operation of said chain-stitching mechanisms.

7. A machine for rooting hair into a doll's head comprising a support, chain-stitching mechanisms including plural needles simultaneously movable through stitch-

forming strokes for chain stitching plural hairs into said doll's head, hair-cutting mechanisms spaced from said needles, means adjustably mounting said hair-cutting mechanisms in said support, means for releasably securing said hair cutting mechanisms in an adjusted position in relation to said plural needles thereby establishing the length of the hair to be rooted into said doll's head, a loop-drawing carriage including plural hair guides pivotally mounted on said carriage, means mounting said carriage for reciprocal movement in a loop-drawing path including a needle-engaging segment in which said plural hairs are individually engaged about the respective needles and said loop-drawing path further including a cutter-engaging segment during which said plural hairs are engaged in said hair-cutting mechanisms, means for adjusting the length of said loop-drawing path to correspond to said adjusted position of said hair-cutting mechanisms, actuating means for said carriage moving the same along the adjusted loop-drawing path, and further actuating means for said hair-cutting mechanisms for severing hair loops in timed relation to operation of said chain-stitching mechanisms.

8. A machine for rooting simulated hair into the skull of a doll's head comprising a work support over which said doll's head is moved, chain-stitching mechanisms including a needle movable through a stitch-forming cycle having a forward skull-penetrating stroke into a hair-pickup position and backward chain-forming stroke, hair-cutting mechanisms including a fixed cutter and a mov-
